CALF FEEDER OR SIMILAR ARTICLE

Kenneth L. Swanson, New Holland, Ohio, assignor to New Holland Feed and Farm Supply Company, New Holland, Ohio, a corporation of Ohio

Application April 5, 1952, Serial No. 19,202

Term of patent 14 years

(Cl. D12—2)

To all whom it may concern:

Be it known that I, Kenneth L. Swanson, a citizen of the United States, residing at New Holland, in the county of Pickaway and State of Ohio, have invented a new, original, and ornamental Design for a Calf Feeder or Similar Article, of which the following is a specification, reference being had to the accompanying drawing, forming a part thereof.

Fig. 1 is a perspective view of a calf feeder or similar article, showing my new design;

Fig. 2 is an end elevational view; and

Fig. 3 is a side elevational view thereof.

The side and end of the calf feeder not shown in the drawing are identical to the side and end as shown in Figs. 2 and 3.

I claim:

The ornamental design for a calf feeder or similar article, substantially as shown and described.

KENNETH L. SWANSON.
